DESIGN FOR A BEDSPREAD

Harriette A. Lawson, Signal Mountain, Tenn.

Application January 13, 1939, Serial No. 82,335

Term of patent 3½ years

To all whom it may concern:

Be it known that I, Harriette A. Lawson, a citizen of the United States, residing at Signal Mountain, county of Hamilton, and State of Tennessee, have invented a new, original, and ornamental Design for Bedspreads, of which the following is a specification, reference being had to the accompanying drawing, forming part thereof.

The figure of the drawing is a plan view of the bedspread showing my design.

I claim:

The ornamental design for a bedspread, substantially as shown.

HARRIETTE A. LAWSON.
